AIR CONDITIONER FRONT PANEL

Charles W. Sanders, Greenville, Mich.

Application January 30, 1956, Serial No. 39,972

Term of patent 3½ years

(Cl. D62—4)

Figure 1 is a top plan view of an air conditioner front panel embodying my new design; Figure 2 is a side view in elevation; Figure 3 is an end view in elevation; and Figure 4 is a sectional side view taken along lines 4—4 of Figure 2.

I claim:

The ornamental design for an air conditioner front panel, substantially as shown.
